Attorney

UNITED STATES PATENT OFFICE.

FLOYD L. SCOTT, OF HOUSTON, TEXAS, ASSIGNOR TO HUGHES TOOL COMPANY, OF HOUSTON, TEXAS, A CORPORATION OF TEXAS.

MOUNTING FOR DRILL CUTTERS.

Application filed October 20, 1925. Serial No. 63,672.

My invention relates to a mounting for the rotary cutters of an earth boring drill. It is intended as an improvement upon the structure shown in the patent to Hughes, No. 5 930,759, granted August 10, 1909.

In this type of drill, the cutters surround the ends of the converging pins upon which they are mounted and are ordinarily retained on said pins by contact of said cutters 10 with each other. When the cutters are suspended on the drill head, they will slide down on the pins into contact with each other. This happens when the drill with the cutters thereon is introduced into the hole. When the cutters strike the bottom they are forced upwardly on the pins until they are again spaced apart in operative position. The disadvantage of this mounting 15 the cutters lies in the fact that the cutters, by moving inwardly into contact with each other, and away from the side of the hole thus have the effect of narrowing the gauge of the drill during the time the drill is going down into the well bore. It is thereby not 20 adapted to ream the hole to full gauge as it is inserted.

It is an object of my invention to provide a means of holding the cutters of an earth-boring drill apart to the extent of their 25 widest drilling position, so that the cutters may be employed to ream the hole to full gauge as the drill is introduced into the well. It is also desired that the cutters be mounted upon bushings of such shape as to give 30 the cutters the maximum turning movement consistent with safety.

Other objects lie in the particular construction and arrangement of parts which will be set out in detail in the specifications 35 which follow.

Referring to the drawing herewith, Fig. 1 is a broken side elevation of a drill with the cutters mounted thereon, said cutters and their supporting pins being in central vertical section. Fig. 2 is a plan view of the spreader element employed with the invention. Like numerals of reference are employed to designate like parts in all the 45 views.

The drawing shows the broken lower end 50 of a drill bit head 1, made up of two parts fitted together along a central plane 2. The lower end of the head is formed with an inverted V shaped slot therein, thus provid-

ing two outwardly inclined faces 3, 3. The 55 bearing pins 4, 4 project inwardly from the faces 3, adjacent the lower edges of the head. Said pins are integral with the head and have a cylindrical threaded portion, 5 and a smooth outer end 6 of smaller diameter. There is an oil duct 7 extending centrally of each of the pins as is usual with 60 this type of tool.

The bushing 8 is a sleeve or cap fitting upon the pin and threaded in position. The 65 outer end is tapered at 9 and projects beyond the pin and is cut with a transverse slot 10 to receive a screw driver or wrench by means of which the bushing may be screwed upon the pin. It will be noted that the slot 10 is 70 shown in end view in the cutter at the left and in side view in the cutter at the right, in the drawing.

The cutters 11 are approximately frusto-conical and shaped internally to fit the bushings 8. 75

Washers 12, separate the cutters from the faces 3 and thus take up the wear from the head at the inner sides of the cutters. The apex of each cutter is formed with a cup-shaped recess 13 of sufficient depth to receive a head 14, of the spreader pin 15. Said pin may be approximately cylindrical with a frusto-conical shaped head 14, at each end, the said heads being inclined upwardly toward, and in alignment with, the central axes of the pins upon which the cutters rotate. 85

The cutters have teeth 16 cut thereon, as is usual, to cut and disintegrate the bottom 90 and side walls of the hole as the drill is rotated.

In operation the cutters will be mounted upon their bushings before the halves of the head are assembled in the position shown 95 in Fig. 1. Then, as the halves of the head are brought together the spreader pin 15, is set in position with the heads 14 thereon fitting within the sockets 13 in the ends of the cutters and thus acting to retain them in operative position. The drill may then be rotated as it is inserted into the hole, and the cutters will be held outwardly so that they will cut the full gauge of the hole. In 100 thus reaming the hole the central bottom portion of the cutters, adjacent the spreader 15, will do very little cutting and there will be no appreciable wear thereon. When the 105

drill reaches the bottom of the hole ready to continue in the drilling of the hole, there will be pressure on the pin, but the pin 15, may wear out or break and no injury will result; for the reason that the pressure of the cutters on the bottom will hold them spread to their full gauge thereafter until the cutters have to be again withdrawn.

By employing the spreader pin with the 10 cutters an operator is enabled to construct the bearings in the form shown and described. There need be no cutter locking or retaining means, thus avoiding an item of expense and trouble.

15 Furthermore, the bushings may be made smaller at their largest diameter, and cylindrical so that the cutters may turn more easily, because of the longer distance between the point of contact of the cutter teeth on 20 the bottom of the hole, and the bushing. There will thus be less wear on the bushings with a resulting longer life.

What I claim as new and desire to protect by Letters Patent is:

25 1. In a roller earth-boring drill including a head having an inverted V shaped recess at the lower end thereof, and converging cutter pins on faces of said recesses, the combination of bushings on said pins, frusto-conical cutters mounted rotatably on said bushings, and a spreader pin between the apices of said cutters to retain them rotatably apart.

30 2. In a roller earth boring drill including a head divided longitudinally, and converging cutter pins on the lower edge thereof, the combination of frusto-conical cutters rotatable on said pins, said cutters having sockets in the forward ends thereof and a spreader

element fitting in said sockets and acting to 40 maintain said cutters spaced apart.

3. In a roller earth-boring drill including a longitudinally divided head and converging cutter pins formed on the lower end of said head, the combination of bushings on 45 said pins, cutters having central recesses to fit over and enclose the ends of said bushings, and means externally of said cutters to hold them rotatably apart.

4. In a roller earth boring drill having a 50 longitudinally divided head and converging cutter pins formed on the lower end of said head, the combination of bushings on said pins, said bushings being approximately cylindrical with forwardly tapered ends, cutters having central recesses to fit over the 55 ends of and receive said bushings, and means between the points of said cutters to hold them apart in the manner described.

5. In a roller earth boring drill including 60 a head divided longitudinally into a plurality of parts, and downwardly converging cutter pins on the lower end thereof, the combination of cutters thereon tapered forwardly and inwardly, and means between 65 said cutters to hold them spaced apart while said cutters are rotated.

6. In a roller earth boring drill including a head having a transverse inverted V-shaped recess in the forward end thereof, 70 cutter pins on said head converging forwardly, cutters mounted rotatably on said pins, and means between said cutters to retain them spaced rotatably apart.

In testimony whereof, I hereunto affix my 75 signature, this the 14th day of October, A. D., 1925.

FLOYD L. SCOTT.
